UNITED STATES PATENT OFFICE.

JAMES LOGAN JACKSON, OF WILLIAMSPORT, PENNSYLVANIA.

CAMERA ATTACHMENT.

SPECIFICATION forming part of Letters Patent No. 703,421, dated July 1, 1902.

Application filed October 25, 1901. Serial No. 79,952. (No model.)

To all whom it may concern:

Be it known that I, JAMES LOGAN JACKSON, a citizen of the United States, residing at Williamsport, in the county of Lycoming and 5 State of Pennsylvania, have invented a new and useful Camera Attachment, of which the following is a specification.

This invention relates to photographic cameras, and has for its object to provide for cutting off from the lens thereof reflected light from adjacent objects and to permit the direct light-rays only striking the lens, thereby to obtain a clear-cut impression upon the sensitive member.

15 It is furthermore designed to arrange for applying the present device either directly to the lens-tube or to the front of the camera, as may be convenient or necessary, and to facilitate the application and removal there- 20 of without interfering with any of the other parts of the camera or requiring any adjustment or rearrangement thereof.

Another object is to have the device collapsible, so that it may be folded into compact form for convenience in carrying the device when not applied to the camera.

With these and other objects in view the present invention consists in the combination and arrangement of parts, as will be herein- 30

after more fully described, shown in the accompanying drawings, and particularly pointed out in the appended claims, it being understood that changes in the form, proportion, size, and minor details may be made 35

within the scope of the claims without departing from the spirit or sacrificing any of the advantages of the invention.

In the drawings, Figure 1 is a perspective view showing the device applied to the front 40 of a camera. Fig. 2 is a longitudinal sectional view of the device. Fig. 3 is a transverse sectional view taken on the line 3 3 of Fig. 2. Fig. 4 is a perspective view of the collapsible frame of the device. Fig. 5 is a 45 detail perspective view of the fastening means employed in the application of the device as illustrated in Fig. 1. Fig. 6 is a detail view illustrating a modified form of fastening means for the device.

50 Like characters of reference designate corresponding parts in all the figures of the drawings.

In photographic work, particularly in making outdoor exposures, sensitive plates or members are often ruined or at least materially impaired by the action of light reflected from adjacent objects which are not in the range of the lens, and to overcome this objection or difficulty I have designed to prevent reflected light from striking the lens by 55 providing a flared tube 1, formed of some dark material and having its smaller end constructed for connection with the front or lens-tube of a camera, so as to embrace the lens, the camera-box being illustrated at 2 in 60 Figs. 1, 2, and 3 of the drawings. By this means the reflected light-rays from adjacent objects are effectually cut off and prevented from striking the lens and the direct light-rays only from the object to be photographed 65 are capable of striking the lens, whereby a clear-cut impression is made upon the sensitive member of the camera. It will here be noted that the essential feature of the present invention is to provide a shield which is 70 open at opposite ends and embraces and projects forwardly from the lens so as to cut off reflected light, the general shape of the shield being conical or flared outwardly, the manner of attaching the shield being of minor im- 75 portance.

I prefer to have the shield collapsible, and therefore provide a frusto-helical frame 3, formed from a single length of wire and inclosed within a cover 4, of some dark textile 80 fabric, whereby the device may be collapsed so as to lie entirely within the outer or larger end portion of the frame, whereby the shield may be conveniently carried in a pocket of the clothing or in a casing for carrying the 85 camera-box.

For convenience in connecting the shield to a camera I have shown one form of attachment in Figs. 2 and 3 of the drawings, where- 90 in the smaller end of the shield is provided 95 with a metallic ring or collar 5, which is pro- vided at diametrically opposite points with outwardly-directed reversely-disposed hooks 6 for engagement with headed pins or pro- jections 7, provided upon the front of the 100 camera and at opposite sides of the lens-tube, whereby the shield may be conveniently ap- plied to the camera and also readily removed therefrom without affecting the lens or re-

quiring any adjustment or rearrangement of parts of the camera.

In some cases—as, for instance, where the lens-tube projects at a sufficient distance in front of the camera—the smaller end of the frusto-helical frame may be snapped or sprung upon the projected end of the lens-tube, thereby requiring no additional fastenings for supporting the shield upon the camera.

Another form of attachment has been shown in Fig. 6, wherein the smaller end of the shield is provided with a split ring or clamp 8, having its opposite ends provided with outwardly-directed ears 9, which are pierced by a set-screw 10, the clamp being designed to embrace the projected end of a lens-tube and to be firmly held thereon by adjustment of the set-screw.

From the foregoing description it is apparent that the present invention is essentially in the nature of an attachment to cameras and is not restricted to any particular type of camera nor to outdoor work alone, as it may be used for interior work whenever required, according to the judgment of the operator.

Furthermore, it is not essential that the device be collapsible, nor is it essential that the shape thereof be conical, as illustrated in the drawings, for it may be polygonal instead of circular in cross-section, although the frusto-conical shape is preferred as being the most successful embodiment of the invention.

What I claim is—

1. As a new article of manufacture, a col-

lapsible frusto-helical wire frame, and a flexible cover carried by and embracing the periphery of the frame, the opposite ends of the article being open.

2. A device for excluding reflected light from the lenses of cameras, comprising a tapered and collapsible tube formed of light-excluding material, the opposite ends of the device being open.

3. A device for excluding reflected light from the lenses of cameras, comprising a tube formed by a collapsible frusto-helical frame, and a flexible light-excluding cover therefor, the opposite ends of the device being open.

4. A device for excluding reflected light from the lenses of cameras, comprising a tube formed by a collapsible frusto-helical frame, a flexible light-excluding cover therefor, and attaching means carried by the smaller end of the device, the opposite ends of the device being open.

5. As a new article of manufacture, a flexible frusto-helical wire frame, a flexible cover carried by and embracing the periphery of the frame, the opposite ends of the article being open, and means carried by the smaller end of the article for mounting the same upon a support without obstructing the open end thereof.

In testimony that I claim the foregoing as my own I have hereto affixed my signature in the presence of two witnesses.

JAMES LOGAN JACKSON.
